UNITED STATES PATENT OFFICE.

JASON C. STEARNS, OF WORCESTER, MASSACHUSETTS.

ELECTRIC-LAMP FITTING.

1,115,032.

Specification of Letters Patent.

Patented Oct. 27, 1914.

Application filed March 18, 1914. Serial No. 825,711.

To all whom it may concern:

Be it known that I, JASON C. STEARNS, a citizen of the United States, residing at Worcester, in the county of Worcester and 5 State of Massachusetts, have invented a new and useful Electric-Lamp Fitting, of which the following is a specification.

This invention relates to an electric lamp connection which, while capable of general use, is particularly adapted for automobile lamps. These lamps as generally made are provided with external drawn or spun-metal casings which serve as the frame-work for the lamp, support the reflector and other 10 external parts, and also in one of the systems serve to constitute one terminal, being metallically connected with the chassis or frame of the car. These casings have to be perforated and a connector inserted and as 15 this has been done heretofore after the casings have been lacquered and treated by heat so as to fix the lacquer or other finish to the surface, it has been a matter of some difficulty and expense to provide a neat appearing 20 joint where the bushing is secured to the lamp frame. It will be understood, of course, that these connectors ordinarily are made up complete, containing the insulating 25 parts and the electrical connecting parts and 30 are then applied to the casings. With this mode of manufacture, all the parts have to be finished before the joint is made and consequently the formation of the joint is a 35 matter which takes considerable time and is expensive in the manufacture of these articles.

The principal object of this invention is to provide for reducing this expense and at the same time producing an article which 40 has a more thoroughly finished appearance on the outside. This is accomplished by treating the outside portion or bushing of the electrical connector as a separate unit and integrally uniting it to the casing of the 45 lamp before the other parts are applied to it so that the joint can be formed in the ordinary metal working ways and the finish on the outside applied to these two parts simultaneously so that it will cover the joint. 50 After this the other parts of the connector are applied and assembled, which can be done in such a way as not to interfere with the finish that has been applied.

Reference is to be had to the accompanying drawings in which,

Figure 1 is a longitudinal, central, sec-

tional view, with parts shown in elevation, showing a three-wire connector arranged in accordance with this invention, and Fig. 2 is a central, sectional view of a portion of the casing and one-wire connector arranged also in accordance with this invention.

In the form shown in Fig. 1, the lamp itself comprises a spun-metal casing *a* receiving a reflector *b* inside, which supports a pair of lamp sockets *c* and *d* for a main lamp *e* and an auxiliary lamp *f*, the purposes of which lamps are well understood. In this case the first step in assembling the casing *a* and the bushing *g* which constitutes a part of the electrical connector after these parts are themselves made up, is to perforate the casing *a*, insert the bushing *g* and braze them together so that they are integrally connected. It is understood of course that at this time the bushing *g* is in its final form and that no metal working operations have to be performed upon it after it is brazed to the casing. This having been done these parts, which are entirely of metal, are lacquered or otherwise treated to provide them with a finished surface, (shown at *S* in Fig. 2) and then baked or otherwise heat treated for the purpose of fixing the same thereon. In this way the external surface of the casing *a* and bushing *g* are provided with one continuous finished coating. All irregularities at the brazed joints are covered and sealed by this coating so that the brazing of the joint is a much less delicate operation than has been the case heretofore. This having been done, an insulating block *h* is removably inserted in the inner end and connected up with ferrules *j* and conductors *k*.

The details of the connector shown in Fig. 1 are not gone into in detail for the reason that I prefer to describe the details of a one-wire connection as shown in Fig. 2. In this case the bushing *G* is brazed to the casing *A* as described in connection with Fig. 1. The inner end of the bushing *G* being screw-threaded, an insulating block *H* is inserted having thereon a rod *L* which extends through a perforation in the center of the block. This block *H* is readily removable from the inside by unscrewing it. This rod is provided with a head at its outer end and a spring *M* is arranged under the head to hold the rod in its outermost position normally. The inner end of this rod is screw-threaded so that it can be applied to a ferrule

2
 5 O, shown as of metal, into which the end of one of the conductors K extends. In order to fasten the conductor firmly in the ferrule O and also to secure it to the rod L which 10 serves as one terminal of this connector, the rod is screwed through a perforation in the ferrule against the end of the conductor. In this way the conductor is held firmly to the rod and operates with it. This form of 15 connector is used in connection with a plug P of insulating material having a metallic socket Q for engaging the end of the rod L, when the plug is inserted in the bushing G, and this lining Q constitutes the other terminal of the connector and is provided with 20 a screw R leading to the conductor.

It will be understood of course that this invention can be used in connection with two-wire or four wire constructions and that 25 other changes in relative arrangement of parts and details of construction can be made without departing from the scope of the invention as expressed in the claims. Therefore I do not wish to be limited in these 30 respects but

What I do claim is:—

1. The combination with a metal casing having a metallic bushing extending therethrough, of an insulating block removably 35 mounted in the end of said bushing and having a perforation therethrough, a conducting rod extending through said perforation, a spring for yieldingly holding said rod in position, a contacting ferrule located 40 transversely of said rod, and a conductor extending into said ferrule, said rod being secured in the ferrule for the purpose of securing it to the conductor and forming an 45 electrical connection.

2. The combination with a metal casing having a metallic bushing extending therethrough, of an insulating block in the inner 50 end of said bushing and having a perforation therethrough, a conducting rod extending through said perforation, a spring inside said bushing engaging said rod for holding said rod in its outermost position, a contacting ferrule located transversely of said rod, a conductor extending into said ferrule, 55 said ferrule being movable with the rod, and a contacting plug having an insulating body adapted to fit within said bushing and provided with a metal-lined socket in the end for engaging the head of said stud and forming an electrical contact therewith.

3. The combination with a thin metal

casing having a metallic bushing extending therethrough and integrally united therewith, said bushing and casing having a continuous surface coating fixed thereto by heat treatment, of an insulating block removably mounted in the end of said bushing and having a perforation therethrough, a conducting rod extending through said perforation, a spring for yieldingly holding said rod in 60 position, a contacting ferrule located transversely of said rod, and a conductor extending into said ferrule, said rod being screw-threaded into the ferrule for the purpose of securing it to the conductor and forming an 65 electrical connection.

4. The combination with a thin metal casing having a metallic bushing extending therethrough and integrally united therewith, said bushing and casing having a continuous surface coating fixed thereto by heat treatment, of an insulating block screwed into the inner end of said bushing and having a perforation therethrough, a conducting rod extending through said perforation, a spring inside said bushing engaging said rod for holding said rod in its outermost position, a contacting ferrule located transversely of said rod inside the casing, a conductor extending into said ferrule, said rod being screw-threaded into the ferrule for the purpose of securing it to the conductor and forming an electrical connection, said ferrule being movable with the rod, and a contacting plug having an insulating body 85 adapted to fit within said bushing and provided with a metal-lined socket in the end for engaging the head of said stud and forming an electrical contact therewith.

5. The combination with a metallic bushing, of an insulating block removably mounted in the end of said bushing and having a perforation therethrough, a conducting rod extending through said perforation, a spring for yieldingly holding said rod in position, 90 a contacting ferrule located transversely of said rod, and a conductor extending into said ferrule, said rod being screw-threaded into the ferrule.

In testimony whereof I have hereunto set 95 my hand, in the presence of two subscribing witnesses.

JASON C. STEARNS.
